United States Patent Office

Des. 204,913
Patented May 24, 1966

204,913

SLIDE FRAME

Roy B. Perschy, Gardena, Calif., assignor to Northrop Corporation, Beverly Hills, Calif., a corporation of California

Filed July 29, 1965, Ser. No. 86,354

Term of patent 14 years

(Cl. D61—1)

FIG. 1 is a front elevational view of a slide frame showing my new design;

FIG. 2 is a right-side elevational view thereof;

FIG. 3 is a top plan view thereof;

FIG. 4 is a bottom plan view thereof; and

FIG. 5 is a perspective view thereof.

I claim:

The ornamental design for a slide frame, as shown.
